UNITED STATES PATENT OFFICE.

EVERETT H. BARNEY, OF SPRINGFIELD, MASSACHUSETTS.

SKATE-FASTENING.

SPECIFICATION forming part of Letters Patent No. 359,493, dated March 15, 1887.

Application filed February 10, 1887. Serial No. 227,199. (No model.)

To all whom it may concern:

Be it known that I, EVERETT H. BARNEY, a citizen of the United States, residing at Springfield, in the county of Hampden and State of Massachusetts, have invented new and useful Improvements in Skate-Fastenings, of which the following is a specification.

This invention relates to skates and pertains to improvements in fastening devices therefor; and the invention consists in the peculiar construction and arrangement of the said fastening devices, all as hereinafter fully described, and pointed out in the claims.

In the drawings forming part of this specification, Figures 1 and 2 are perspective views of a skate provided with devices for securing the same to a shoe, constructed according to my invention, Fig. 1 showing the skate in connection with the sole and heel of a shoe. Figs. 3, 4, and 5 are plan and side elevations of detail parts of portions of the fastening devices, (somewhat enlarged,) which are hereinafter fully described.

In the drawings, 4 indicates the runner, and 2 and 3, respectively, the sole and heel plates, of the skate, said plates and runner being constructed and secured one to the other in the ordinary way; also, the heel-clamp 5, having an extension thereon which enters a socket between the two plates which constitute the bracket-support of the heel-plate 3, is of a well-known construction, together with the heel-clamp screw 6, which extends from the rear end of the heel-clamp through the horizontal part of the latter and between said bracket parts, as shown; also, the sole-clamps 9 are constructed and attached to the sole-plate in a well-known manner, whereby when they are, by the lever and by the screw-rod parts of the fastening devices, given a longitudinal movement under the sole-plate 2 their upturned ends *x* are clamped against and released from the edges of the shoe-sole. The hereinafter-described peculiarly-constructed pivot 10 constitutes the pivotal connection of the rear ends of the sole-clamps 9.

The essential features of this invention consist in the peculiar construction and arrangement of the sole-clamp and lever-pivot 10, the clamping-lever 12, and the combined nut and yoke 7, which connects the screw-rod 6 with the said sole-clamp pivot. The said pivot 10

is partly shown in side views in Figs. 1 and 2 in connection with the rear ends of the sole-clamps 9, the end of the clamping-lever 12, 55 and the forward end of the nut-yoke 7, and it is shown in top plan view in Fig. 3, the forward end of said yoke being shown broken off in the last-named figure. Fig. 4 shows a clear side elevation of said pivot, the ends of 60 the clamps 9, the yoke 7, and lever 12 being shown in section in this figure, so that the form of said pivot may be seen and understood. A screw, 8, entering the lower end of the pivot 10, serves to secure the lever 12 thereto. 65

The shank *z* of the pivot 10 is cylindrical and is surmounted by a disk-like head, *o*, whose periphery is eccentric to the shank *z*, and to one side of the axis of said shank is fixed the stud *c*, so that when the pivot 10 is 70 rotated said stud has a crank-motion. The circular parts of the opposite sides of the lower end of the pivot-shank *z* are removed, giving the lower end of the pivot an oblong form transversely of its axis and making said sides 75 parallel, as shown in dotted lines in Fig. 3 and in side view in Fig. 4, in order to adapt said lower end to enter the perforation *w* in the clamp-lever 12. The said parallel sides on the lower end of the pivot 10 are, however, so 80 formed that they extend in a plane inclined to a longitudinal line, *y y*, drawn centrally across the end of said pivot and its stud *c*. Thus, when the stud *c* on the pivot is brought to the position it occupies as shown in Fig. 3, when 85 the greatest locking strain is exerted on the skate-fastening parts, the locking-lever 12 is swung quite under the yoke 7 and the screw-rod 6, and no drawing strain on stud *c* is effective to swing the free end of lever 12 outward. 90

The position of the stud *c*, as shown in Fig. 3, relative to the longitudinal center line, *y y*, clearly shows that the axial center of said stud is brought exactly under said line *y*, and that 95 therefore the said stud does not to any degree pass to one side of the axial line of the shank *z* of the pivot 10. Therefore the locked position of the stud *c* does not contribute to hold the free end of the lever 12 in a locked position under the skate, as it would do if said pivot swing partly or wholly past the line *y* when the skate is locked on the shoe.

To provide for retaining the lever 12 firmly

under the skate, with an inclination to swing more and more toward a locked position, (or that shown in Figs. 3 and 4,) the sides of the lower end, *v*, of the pivot 10 are formed inclined to said line *y*, as above described, and the sides of the perforation *w*, through the lever 12, which receives the said end *v* of the pivot, are correspondingly inclined, as shown. The effect of the above-described peculiar pivot 10 and connection is to cause the lever to remain in a locked position when the center of the stud *c* is coincident with the longitudinal center line, *y*.

A further means for causing the lever 12 to be held in a locked position under the skate by the strain on the fastening devices consists in the peculiar construction of the yoke 7. Said yoke is pivoted by one end to the stud *c* of the pivot 10, and from thence extends rearwardly toward the heel-plate of the skate, and its rear end is bent downward and is tapped to receive the screwed end of the rod 6, and thereby the yoke becomes the connection between the heel and sole-clamps of the skate. Below said screw-rod point of connection with the yoke 7 there is formed in the latter a transverse slot, *a*, extending from one edge of the yoke, just above its downhanging end, to receive the part *b* of the lever 12, the part *e* of said lever, on which is the thumb-piece *d*, being offset, as shown, to permit said part *b* to enter the said slot *a*, while the part *e* lies close against the heel-plate bracket, as it does when the lever is brought to a locked position, or to that shown in Figs. 3 and 4.

Fig. 2 shows the position of the locking-lever 12 when swung forward to release the clamps.

When the greatest locking-strain is exerted on the fastening devices of the skate, said strain is in the line of the rod 6 and the yoke 7, whereby the stud *c* is strongly drawn toward the heel-plate 3. This strain action causes the pivot 10 to be more or less canted or swung, so that the axis of its shank is vertically inclined, thereby causing the end of the lever 12, when brought around against the pending end *n* of the yoke 7, to hang down below the end of the slot *a*, as shown in Fig. 1; and to enter the lever in said slot its free end must

be sprung forward, and therefore when the lever is forced into the slot, as in Fig. 4, it has such a frictional contact or bearing against the lower side of said slot that the lever cannot be jarred or shaken out of it, thereby providing further security against the accidental displacement of the locking-lever.

What I claim as my invention is—

1. Mechanism interconnected between the sole-clamps and the heel-clamp screw-rod of a 60 skate, consisting of a pivot, 10, passing through the rear ends of the sole-clamps and having a stud, *c*, thereon to one side of its axial line, a yoke, 7, pivoted by one end on said stud and having its opposite end bent downward and 65 tapped to receive the end of a screw-rod, 6, and having a transverse slot, *a*, therein extending from one edge thereof, and a lever, 12, connected to said pivot 10 and having an engagement in said slot, combined with said 7c sole-clamps and screw-rod, substantially as set forth.

2. In combination, the sole-clamps 9, the pivot 10, constituting the pivotal connection of said clamps, having the stud *c* on one end thereof to one side of its axial line and having its lower end of oblong form transversely, whose sides extend in a plane inclined to a line across the end of said pivot and stud, a lever, 12, having a perforation to receive the lower 8c end of said stud, the sides of which are inclined longitudinally, substantially as described, a yoke, 7, having a pivotal connection on said stud, and a screw-rod, 6, connected with the heel-clamp and with said yoke, sub- 85 stantially as set forth.

3. In combination, the sole-clamps, the screw-rod 6, the pivot 10, having the stud *c* thereon, the yoke 7, connected to said pivot and screw-rod and having the slot *a* therein, 90 and the lever 12, attached to said pivot and having the offset portion *e* near its free end, whereby the lever is permitted to enter said slot when said portion *e* lies against the heel-plate bracket, substantially as set forth.

EVERETT H. BARNEY.
